KEY HOLDER
 Charles E. Morris, Elberon, N.J.
 (10 Wilson Ave., Oakhurst, N.J.)
 Filed June 1, 1960, Ser. No. 33,311
 3 Claims. (Cl. 70—456)

The invention herein disclosed relates to devices for holding a group of commonly used keys and the objects of the invention are to provide a simple inexpensive form of container which will hold the keys in compact relation, covered and protected but readily accessible for use.

Particularly it is a purpose of the invention to provide such a holder in a small light weight size which, while fully covering the blade or active portions of the keys, will leave the head or handle portions sufficiently exposed for the convenient separation and use of the selected keys.

The objects mentioned and further desirable objects attained by the invention and the novel features of construction, combination and relation of parts comprising the invention are set forth and will appear in the course of the following specification.

The drawing accompanying and forming part of this specification illustrates a present practical embodiment of the invention. Structure however may be modified and changed as regards the immediate illustration, all within the true intent and scope of the invention as hereinafter defined and claimed.

FIG. 1 in the drawing is a plan view of the key holder in closed condition.

FIG. 2 is an edge view of the same in the open condition and with parts broken away and appearing in section.

FIG. 3 is a plan view of the reverse side of the holder.

FIG. 4 is an end view of the holder in open relation.

As shown in the several views the holder of this invention comprises a narrow, elongated form of container 7 for the blade portions of the keys and spaced parallel sides 8, 9 extended from opposite sidewalls of the container and of a length to confine between them the head or handle portions of the keys.

The container is shown as of rectangular cross section, large enough to freely receive the blades of the keys and the head confining extensions 8, 9 are shown as of the same approximate width as the top and bottom walls 10, 11 from which they project.

The heads of the keys are rotatably held in the confining extensions 8, 9 by a pivot stud shown in the form of an elongated eyelet 12 flanged at one end at 13 and having radially projecting lugs 14 at the opposite end which can pass through a correspondingly radially notched opening 15 in the other extension.

These radially projecting lugs may be turned out after first passing the eyelet through the circular opening 16 provided for it in the extension 8.

This eyelet with the outstanding lugs is of a size to pass through the openings in the heads of the keys so that after threading the eyelet through a group of selected keys the eyelet may be passed through the notched opening in the second extension and be turned to seat the lugs into holding recesses 17 provided to receive the same in the second head confining extension.

A resilient washer 18 of sponge rubber or the like is seated beneath the flange or head 13 of the eyelet to apply sufficient tension to hold the eyelet against turning and thus releasably locked in place.

Turning of the eyelet to release it or to locate it in the detent position may be effected by a coin, knife blade or the like engaged in a cross slot 19 provided in the flanged end of the eyelet.

2

The keys are held with the blades covered and confined in the container portion by a hinged cover 20 which, in the illustration, forms approximately one half the cross sectional structure of the container.

5 The end view FIG. 4 shows how this cover is made up of one wall 21 of the full extent of one wall of the container and two wall extensions 22, 23 of approximately half a complete side wall of the container, providing a hollow cover of approximately half the cross section of the container and therefore adapted to fully open up the container for movement of the key blades into and out of the same.

This hollow cover is shown pivoted on a longitudinally extending hinge pin 24 carrying a coiled spring 25 for snapping the cover into the fully open position.

A retainer for securing the cover in closed relation is shown in the form of a projecting clip 26 on the edge of the cover positioned to snap over a ridge 27 embossed on the opposing edge of the container wall 10.

20 The container may be made of a soft metal which will be work hardened in the embossing and drawing operation to a finished spring temper. This will give the container a spring quality such that the cover may then be released by simply squeezing or pinching the opposing front and back walls 10, 11 of the container toward each other and whereupon as the catch 26 releases hold on the ridge or corrugation 27 the spring 25 will snap the cover into the open position shown in FIGS. 2 and 4.

25 The ridge or corrugation 27 in the front wall may be extended on into the head confining extension 8 as shown at 28 in FIG. 1 and similarly a ridge or corrugation 29 may be embossed on the back extension in line with the hinge pin, reinforcing and stiffening these parts and enabling them to be made up of light sheet material.

30 To enable quick selection of keys the edges of the front and back extensions 8 and 9 are shown as notched at 30 for insertion of a thumb to rotate a selected key out into position where it can be grasped by the fingers and turned out sufficiently for convenient use.

35 For a small number of keys the container portion of the holder may be substantially square in cross section and providing a small unit but slightly larger than the width and length of the contained keys.

40 The head confining extensions 8 and 9 being only the width of the container portion expose the heads of the keys projecting beyond opposite edges of the same and hence enable easy identification of the different keys confined in the holder.

45 The fixed half of the container carrying the head confining extensions may be made up as a single stamping and the hollow cover forming the other half of the container similarly may be stamped in a single piece. These parts may be produced at low cost and the eyelet or possibly other form of pivot stud for the keys adds but little to the cost of the complete unit.

50 In addition to its functional uses the holder provides an attractive case for keys ordinarily used and keeps them compactly grouped in a convenient and desirable condition for carrying in a pocket or handbag or the like.

55 Individual keys may be readily placed in the holder or be removed by means of the releasable eyelet pivot. When released the eyelet is held against loss by means of the radially projecting lugs on the inner end of the same.

60 The name of the owner, registration number, advertising matter or the like may be imprinted or engraved on one or all of the sides of the container, after the manner indicated in FIG. 3.

65 Additional reinforcing embossments may be impressed in the material of the holder where desirable, as illustrated, such as the reinforcing ridge shown at 31 in FIG. 1 connecting the body and extension portions of the

holder. This ridge is shown extending from the stationary half of the container into the confining extension connected therewith and a similar reinforcement if desired may be impressed from the opposite side of the container into the confining portion connected with that side.

What is claimed is:

1. A key holder comprising a narrow elongated container for the blade portions of a stack of keys held on a common center, spaced parallel confining portions extending from said container and of an extent to confine the head portions of the keys disposed in said holder, a spring retained eyelet connecting said spaced confining portions and forming a pivotal mounting for the heads of the keys in said holder, said container having a hinged cover in line with the space between said confining portions openable to expose the blades of the keys confined in the holder and a spring clip for releasably confining said cover in closed position, said eyelet having a flange at one end and having projecting lugs at the opposite end, a yielding washer interposed between said flange and one of said confining portions and the other confining portion having notches to pass said lugs on the opposite end of said eyelet and depressed seats between said notches to receive said projecting lugs and hold the eyelet against turning into alignment of the lugs with said notches.

2. A key holder comprising a container of a size to hold the blades of a group of keys stacked in alignment and comprising a longitudinally split substantially rectangular cross section casing having a fixed half and a movable half in the form of a hollow cover hinged thereto, elongated extensions projecting from said fixed half of the container spaced to confine the head portions of

such a stack of keys, a pivot stud for the heads of the confined keys extending between said extensions, a spring clasp for securing the hinged cover in closed relation and a spring for throwing the cover into fully open position when said spring clasp is released.

3. A key holder comprising a narrow elongated container for the blade portions of a stack of keys held on a common center, spaced parallel confining portions extending from said container and of an extent to confine the head portions of the keys disposed in said holder, a spring retained eyelet connecting said spaced confining portions and forming a pivotal mounting for the heads of the keys in said holder, said container having a hinged cover in line with the space between said confining portions openable to expose the blades of the keys confined in the holder, a spring clip for releasably confining said cover in closed position, said cover being substantially half the cross sectional dimensions of the container, leaving a stationary half container portion and a reinforcing ridge extending from said stationary half of the container to the confining portion attached thereto.
